UNITED STATES PATENT OFFICE

CHARLES SPATSCHEIL, OF JERSEY CITY, NEW JERSEY, ASSIGNOR TO SIMON MILLER & CO., OF NEWARK, NEW JERSEY, A COPARTNERSHIP COMPOSED OF SIMON MILLER, OF NEW YORK, N. Y., MORRIS MILLER, OF EAST ORANGE, NEW JERSEY, AND EMANUEL MILLER, OF NEW YORK, N. Y.

BRACELET

Application filed December 26, 1929. Serial No. 416,324.

This invention relates to bracelets and has for its object to provide a bracelet of single piece joints united together and non-soldered to each other or in themselves soldered. Its further object is to provide a bracelet in which there is a double thickness of stock at the parts at which the greatest stresses appear; namely, at the pintles. The invention comprises structures fulfilling these objects and consists of links each formed from a blank, and to the proper shape, and joined together at their edges by pintles having upset ends, without employing solder or similar material in the links themselves or in the joining of the links.

The invention will be hereinafter more fully described in relation to an embodiment thereof shown, in the accompanying drawings, and finally pointed out in the claims.

20 In the accompanying drawings Figure 1 is a plan view of the initial blank of metal,

Figure 2 a perspective view of the same with certain parts thereof bent into position,

Figure 3 a perspective view of the same 25 blank formed into the next stage of operation,

Figure 4 a plan view of a part of the bracelet showing a few links, joined together, and other parts broken away,

Figure 5 a vertical, longitudinal section, 30 broken on line 5—5 of Figure 4, and

Figure 6 a transverse, vertical section on line 6—6 of Figure 4.

Similar characters of reference correspond to like parts throughout the drawings.

35 In the drawings, there is shown in Figure 1, a blank of metal, which, of course, may be of any suitable metal, as silver, gold, platinum or inferior precious character, these blanks in the shape shown in this embodiment being readily stamped out in the shape there shown.

A main body portion 11 to form the top of the link, has two lateral ears 13^a, having openings 13, and a reduced portion 22 cut down at 20 which reduced portion 22 has an opening 19, and which intermediate portion 22 joins with the portion which is to form the bottom part.

This bottom part 12 has lateral portions 16 at the forward ends of which inclined portions 17 are provided and at the rearward end of 45 which openings 15 are provided. These por-

tions 16 are adapted to be bent downwardly substantially at right angles to the part 12, so as to form side members to the link. The part 12 is provided with an opening 18, and both this opening as well as opening 19, are rather ornamental and can be dispensed with as far as the invention is concerned. While not essential it is preferable to form the blank with a slight offset 21 as shown in Figure 2, and not shown in Figure 1, as it adds to the finish of the completed article. After the ears 13^a and side flaps 16 have been bent over the so formed blank appears as shown in Figure 2. The blank so bent is then bent on itself so that the upper portion 11 and lower portion 12 55 face each other as shown in Figure 3, the intermediate portion 22 forming the curved end of the link, and the top and bottom portions are then pressed together until the openings 13 of the ears 13^a come into registration with 60 the openings 14 of the ears 15, whereupon another link equally bent and pressed together is placed in such a position to the first link, that the intermediate or curved end portion 22 of one link enters the open end of the other 65 link and the hollow space enclosed by the intermediate portion 22, is brought into registration with the registering openings 13 and 14, whereupon a pintle 25 is passed therethrough. The free ends of the pintle 22 are 70 then upset as shown by 26 in Figure 6, and these two links are thereby joined together without solder or any similar material. It will be noted that the place where links of a bracelet receive perhaps the greatest stress, 75

the pintle is acted upon by a full face surface of the intermediate portion 22, and the double thickness of metal of the other link in the form of the overlapping ears 13 and 15, is provided, which two adjacent ears co-act at 80 one side of the link with the pintle.

In Figure 5 is clearly shown the cooperation of the offset 21, with the adjacent end portion of the next link whereby the movement of the links is controlled and the bracelet does not buckle reversely. The surface 11 or upper surface rests at the same time upon the curved intermediate portion of the adjacent link giving a freedom of movement and a guiding action to the respective parts.

Both the upper surface 11, the side portion 16, the lower surface 12, and the exposed surfaces of the ears, or any parts thereof, may be chased or otherwise decoratively provided 5 with open spaces in accordance with the usual designing methods to add beauty to the bracelet, but these are not shown in the drawings as taste varies the design.

The links as described are, of course, interchangeable.

The end connecting members are provided with the usual hooks or other fastening means, not shown, as within the skill of the artisan.

My invention distinguishes from the prior art in that heretofore when a blank was used it formed only one surface layer, as in U. S. Patent No. 1,605,077 of November 2, 1926, whereas in my invention the blank is intended to form both top and bottom as well 20 as the intermediate surface, and instead of using a bent over part of the blank, my invention utilizes pintles to strengthen the structure; while it has been proposed to do without the use of solder, this has been 25 done again only with one layer or surface, as shown in U. S. Patent No. 1,735,884 of November 12, 1929. Nor does my invention require springs as in U. S. Patent No. 1,626,139 of April 26, 1927.

My invention distinguishes over the prior art in that each link is complete in itself and form of top, bottom and intermediate parts out of one blank, bent to shape, and simply joined by pintles.

I have described an embodiment of my invention, representing the best form of my invention and the mode of applying it, but changes may be made in the embodiment by the omission or addition of parts thereto, 40 without departing from the principle of my invention as defined in the appended claims.

I claim:

1. A link made of one piece of metal, consisting of a top member, a bottom member, 45 an intermediate member, said top and bottom members having projecting ears in registration with each other and adapted to be engaged by a pintle.

2. A link made of one piece of metal, consisting of a top member, a bottom member, an intermediate member joining the top and bottom members and forming an end portion to the link, and adapted to receive a pintle, and means on the top and bottom members adapted to receive a pintle.

3. In combination, a plurality of links, each consisting of a top, bottom and intermediate member integrally connected, the top and bottom members having means adapted 50 to receive a pintle, the intermediate member having means adapted to receive a pintle, and a pintle engaging the said means of the top and bottom members of one link and the said means of the intermediate member of 55 the other link.

4. A link for bracelets and the like consisting of a sheet metal blank having top and bottom portions of substantially equal area and an intermediate portion connecting said top and bottom portions at one of their ends, 70 said bottom portion having side flanges disposed substantially at right angles to the plane of said portion and engaging the under side of the top portion at its opposite longitudinal edges, and said top and bottom portions being provided at their other ends with means to receive a pintle for connecting the link with an adjacent link and for retaining said top and bottom portions in parallel relation with each other.

5. A link for bracelets and the like consisting of a sheet metal blank having top and bottom portions of substantially equal area and an intermediate portion connecting said top and bottom portions at one of their ends, 80 said bottom portion having side flanges disposed substantially at right angles to the plane of said portion and engaging the under side of the top portion at its opposite longitudinal edges, said flanges at one of their ends and said top portion at its corresponding end having registering apertured ears to receive a pintle for connecting the link with an adjacent link and for retaining said top and bottom portions of the link member in parallel 85 relation to each other.

6. A link of the character described comprising a single piece of metal bent into link formation and defining at one end of the link a curved surface adapted for engagement 100 with a pintle, said link having overlapping ears at the other end, which ears are formed with holes to receive a pintle and adapted to receive the curved pintle engaging portion of an adjacent link.

In testimony that I claim the foregoing as my invention, I have signed my name hereto.

CHARLES SPATSCHIL.
